Primary Examiner — Messina L Smith(57) **CLAIM**

The ornamental design for a coffee grinder, as shown and described.

DESCRIPTION

FIG. 1 is a top, front, right side perspective view of a coffee grinder, showing my new design;

FIG. 2 is a bottom, left side perspective view thereof;

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.
